UNITED STATES PATENT OFFICE.

WALTER MEYNER, OF NEW YORK, N. Y.

TOY.

1,216,589.

Specification of Letters Patent. Patented Feb. 20, 1917.

Application filed June 26, 1916. Serial No. 105,858.

To all whom it may concern:

Be it known that I, WALTER MEYNER, citizen of the United States, and resident of New York, in the county of New York and

5 State of New York, have invented a certain new and useful Toy, of which the following is a specification.

My present invention has for its objects to provide a simple and inexpensive form 10 of toy which will be both interesting and amusing, which will be entertaining to those using it and to onlookers as well and which will be stimulative of healthful exercise.

In a general way the invention consists 15 of a hoop, a movable figure of characteristic or ornamental appearance within the hoop, rollers riding on the inner periphery of the hoop and connected to operate the movable figure and a handle by means of which the device may be trundled along.

Details of the invention will appear as the specification proceeds, attention being directed to the accompanying drawings forming part hereof and wherein I have illustrated the invention embodied in several practical and preferred forms.

In said drawings:

Figure 1, is a perspective view of a form 20 wherein the movable figure is in the nature of a dog or like animal.

Fig. 2, is a similar view, illustrating the movable figure as in the form of a manikin.

Fig. 3, is another perspective view illustrating a simple form of rotary figure device.

Fig. 4, is a like view of another form of the invention.

In the several views, 5, designates the trundle or hoop, made large enough to be 25 easily trundled and to contain within it or support a figure of reasonable size.

In the first form shown the figure, 6, is made in the semblance of a dog or puppy, having movable elements in the shape of the 30 jointed leg sections 7, 8.

9 designates rollers riding on the inner periphery of the hoop and connected in this instance to the movable sections of the figure by cranks 10, on the axles 11, of the rollers which carry crank pins 12, engaging the 35 lower or outermost leg sections 8.

From this it will be seen that as the hoop is rolled along over a supporting surface the rollers will be rotated by their engagement 40 with the inner periphery of the hoop and

will by the connections described, impart a more or less natural movement to the legs, giving the figure the appearance of running along within the hoop.

A handle 13, is usually provided for 45 handling the toy, this handle being shown connected at 14, with the figure and inclined upwardly and rearwardly to afford a convenient handhold for pushing the toy.

A convenient and practical method of 50 constructing the toy is to make it in counterpart sections 15, spaced apart a distance slightly greater than the thickness of the hoop and with portions 16, overlapping the edges of the hoop so as to confine the figure 55 within the hoop, the supporting rollers when journaled between these sections, as indicated, being then disposed in the plane of the track 17, which forms the inner periphery of the hoop. 75

An additional roller 18, or rollers may be provided, the rollers and the confining portions 16 being usually arranged in some- 60 what triangular relation, as shown, so as to hold the parts assembled, without binding. 80

In the second view the figure is in the form of a manikin 18', having jointed leg sections 19, 20, operated by a crank connection similar to and having the same reference characters as in the first view. A grotesque effect is obtained in this construction by pivoting the upper section 21, of the body 65 at 22, and providing outstanding arms 23, which embrace the sides of the hoop and carry rollers 24, 25, bearing on the inner track 17, one of these rollers being journaled eccentrically as shown at 26, to impart a nodding or rocking movement to the upper body section head and arms of the figure. 90

In the third form illustrated, the movable 70 figure is in the shape of a disk 27, loosely confined between spaced members 28, and preferably ornamented by coloring or figured in some attractive way, said disk bearing 100 on rollers 29, having a bearing on the inner periphery of the hoop. 95

In Fig. 4, the object 30 is in the form of a grotesque manikin having bowed legs 31, in which are journaled rollers 32 on eccentric pivots 33, said rollers having a bearing on the track 17, forming the inner periphery of the hoop, said hoop being in this case more in the nature of a disk and the track being formed eccentrically in said disk. A 105 third eccentric roller 34, is shown pivoted 110

at 35 and arranged to bear on the upper portion of the eccentric track. This construction gives the figure a peculiar rising and falling and rocking movement in the disk or hoop and the effect is enhanced by a rotating disk 36, supported on the rollers 32-34.

The invention may be made up very inexpensively since all the parts can be constructed of wood or like material, the device is light and easily handled, simple of construction and entertaining and interesting in its operation.

What I claim is:

- 15 1. A trundle toy comprising in combination, a handle for propelling the toy, a figure within the hoop engaged by said handle and provided with a pivoted section and an eccentrically journaled roller mounted on
- 20 2. said pivoted section and bearing on the inner periphery of the hoop.
- 25 3. A trundle toy comprising a hoop, a member within said hoop having spaced apart sides provided with portions embracing the edges of the hoop, a roller journaled between said spaced apart sides and bearing on the inner periphery of the hoop and a

movable figure device operated by said roller.

3. A toy comprising a hoop, a movable figure associated with said hoop and a roller engaged with said figure and engaging the trackway provided by the inner periphery of the hoop, said trackway, figure and roller bearing an eccentric relation to each other whereby in the rotation of the hoop to impart a rocking motion to the figure.

4. A toy comprising a hoop, a movable figure associated with said hoop and a roller engaged with said figure and engaging the trackway provided by the inner periphery of the hoop, said trackway, figure and roller bearing an eccentric relation to each other whereby in the rotation of the hoop to impart a rocking motion to the figure and a handle connected with the figure for propelling the hoop.

Signed at New York in the county of New York and State of New York this 20 day of June A. D. 1916.

WALTER MEYNER.
